UNITED STATES PATENT OFFICE

149,897

DESIGN FOR A MAGNETIC PENCIL

Richard McFadyen, Upper Montclair, N. J., assignor to Ketcham & McDougall, Inc., East Orange, N. J., a corporation of New Jersey

Application May 1, 1947, Serial No. 138,742

Term of patent 7 years

(Cl. D74—24)

To all whom it may concern:

Be it known that I, Richard McFadyen, a citizen of the United States, residing at Upper Montclair, county of Essex, and State of New Jersey, have invented a new, original, and ornamental Design for a Magnetic Pencil, of which the following is a specification, reference being had to the accompanying drawing, forming a part thereof, in which:

Figure 1 is an elevational view of a magnetic pencil, showing my new design;

Figures 2 and 3 are fragmentary elevational views of the upper portion of the magnetic pencil and taken at right angles from each other.

The essential features of my design reside in

the configuration of the magnetic attachment at the top of the pencil.

I claim:

The ornamental design for a magnetic pencil, substantially as shown and described.

RICHARD McFADYEN.
